CLAIM

The ornamental design for a shopping discount calculator, as shown and described.

DESCRIPTION

FIG. 1 is a front elevation view of a shopping discount calculator showing my new design;

FIG. 2 is a rear elevation view thereof.

FIG. 3 is a left side elevation view thereof.

FIG. 4 is a right side elevation view thereof.

FIG. 5 is a top plan view thereof; and,

FIG. 6 is a bottom plan view thereof.

The broken lines depict environmental subject matter only and form no part of the claimed design.
